UNITED STATES PATENT OFFICE.

GEORGE W. LEVAN, OF PHILADELPHIA, PENNSYLVANIA.

HEEL-CUSHION.

Specification of Letters Patent. Patented June 11, 1912.

1,029,019.

Application filed March 29, 1911. Serial No. 617,689.

To all whom it may concern:

Be it known that I, GEORGE W. LEVAN, a citizen of the United States, residing at Philadelphia, in the county of Philadelphia and State of Pennsylvania, have invented 5 new and useful Improvements in Heel-Cushions, of which the following is a specification.

An object of the invention is to provide 10 a heel cushion for disposal in a shoe in the rear of the instep thereof to cushion the heel of a foot when the same is disposed in the shoe.

For the purpose mentioned, use is made 15 of a plurality of relatively hinged plates and a plurality of springs disposed between the said plates and connected to one of the plates, a suitable material, such as felt or the like being disposed over the upper plate 20 and having a shape substantially the same as the upper plate so that the heel of a foot will not directly contact with the upper plate.

Reference is to be had to the accompanying 25 drawings constituting a part of this specification, in which similar characters of reference denote corresponding parts in all the views, and in which,

Figure 1 is a perspective view of my device, the lower portion of a shoe being shown in dotted lines to denote the relative 30 position of my device in a shoe. Fig. 2 is a longitudinal sectional view taken on the line 2—2 in Fig. 1. Fig. 3 is a transverse 35 sectional view taken on the line 3—3 in Fig. 1. Fig. 4 is a fragmentary perspective view of the under side of one of the plates and having a spring attached thereto.

Referring more particularly to the views, 40 I provide a plate 10 having a shape similar to the heel of a shoe and hingedly mounted on one end of the plate 10 is a second plate 11 similar in shape to the plate 10 and dis-

posed substantially beneath the plate 10. 45 At the side edges of the plate 10 downwardly struck lugs 12 are formed, slots 13 being provided on both sides of each of the said lugs. Springs 15 are provided, preferably having a U-shape with each of the springs disposed to pass through each of the slots 13 on both sides of the plate 10 and over the lug 12. The springs 15 engage the plate 10 adjacent the inner loop thereof and the outer ends 16 of the springs 50 project outwardly from the main body 55 of each of the springs, so that one of the ends abuts against the under side of the plate 10 and the other end abuts against the upper side of the plate 11, thus tending to relatively spread the plates at the outer 60 ends thereof.

A piece of material, having a shape substantially the same as that of the plate 10 is disposed over the plate 10 or secured thereto and when my device is positioned in 65 a shoe at the heel thereof, the heel of the foot will rest on the device and provide a suitable heel cushion for cushioning the foot at the rear thereof.

Having thus fully described the invention 70 what I claim as new, is:—

In a heel cushion the combination with two hingedly connected plates, a downwardly struck lug on each of two opposite sides of one of said plates, a slot formed at 75 each side of each of said lugs, of a pair of U-shaped springs disposed between said plates, one leg of each of said springs extending over one of said lugs and through the slots at the sides thereof. 80

In testimony whereof I affix my signature in presence of two witnesses.

GEORGE W. LEVAN.
